AUTOMATICALLY RETRIEVING FLOATING REEL

James Rudolph Godwin, Bainbridge, Ga.

Application November 20, 1951, Serial No. 257,350

3 Claims. (Cl. 242—89)

This invention relates to reels of the automatically retrieving type with particular reference to reels combined with fluid distribution means.

Although conventionally springs are employed to retrieve a reeled out element, such as hose, it would be especially advantageous to provide a reel which would accelerate the rate at which the hose is retrieved and also the rate at which the hose is played out. Accordingly, one of the main purposes of this invention is to provide a reel which will play out hose, rope, wire or the like at a greatly accelerated pace requiring a minimum of effort, and which will automatically reel in or retrieve the hose into a compact unit.

The field of use for such a reel is diverse. For example, a unit of the above described character, when mounted on wheels is ideally suitable for playing out water hose. Another adaptation would be in combination with garden sprinkling means wherein the reeling unit is combined with a valve controlled sprinkler having one valve position where the hydrant is connected to the sprinkler and another valve position where the hydrant is connected with an extendable hose outlet and a third position where water is supplied to both outlets.

By mounting the reeling unit on a cable, lubricating means may be easily distributed to automobile fittings or the like.

For the purposes of compactness, it would be desirable to arrange a reeling unit in a plurality of tiers whereby more hose length could be accommodated per unit of reel diameter. Moreover, by so distributing the coiled hose length, each tier would retain less material thereby greatly reducing the forces exerted inter-coils. The latter reduction is especially pertinent in the use of fluid distribution means. Obviously, higher inter-coil pressure when partially reeled results in greater resistance to fluid flow, an undesirable result.

Then, another important inventive object relates to the provision of multiple tier reeling units for fluid distribution wherein the reel structure itself forms a part of the flow conduit whereby the resistance to flow through the unit is decreased and the coils can be contained in a compact efficient unit.

A further inventive object relates to the combination of a hose reeling unit of the latter type with a sprinkler unit wherein the hose and sprinkler outlets are valve controlled from the reel unit.

Another adaptation of this invention, the manual effort required to reel the hose in or out is substantially eliminated by employing fluid means to actuate the reel. The reel is constructed with means responsive to fluid pressure and velocity to cause a rotary movement of the winding element. Consequently by merely connecting the reeling unit to a source of fluid pressure, the reeling operation can be effected. Therefore, another inventive object relates to providing an automatic reeling unit wherein reeling is effected by means responsive to fluid pressure and velocity.

2

A further object of the invention relates to providing a reel which grips a hose or the like, at a medial portion and which is so formed that the hose is reeled from both ends in parallel coils, the reel being provided with 5 roller means to facilitate moving the reel unit.

A further inventive object relates to providing a reel of the latter type with spring means so wound as to resist outreeling, an initial tension being present in the spring to insure complete hose retrieving.

10 A further inventive object relates to providing a reel of the latter type with sliding doors, anti-friction roller means and wherein the spring for retrieving is helical.

A still further inventive object relates to providing a reel of the latter type with hose gripping means in the 15 form of an S-shaped groove.

A still further inventive object relates to providing a reeling member having two tiers, one tier being for an inlet hose, the other for an outlet hose, the tiers being interconnected by a valve fitting which also communicates with a sprinkler, the arrangement being such that either the outlet hose or the sprinkler or both can be connected to the inlet hose by means of a valve accessible from the sprinkler head, the reeling member being biased to the fully wound position by spring means.

20 25 A still further inventive object relates to providing a reel which is double tiered and can be wound by rolling the unit along the ground by handle means.

A still further inventive object relates to providing a reel which can be used in conjunction with a cable support to distribute fluid.

30 35 A still further inventive object relates to providing a reel which is manually actuated employing geared means to transmit the driving power.

Other objects and structural details will be apparent 40 from the subjoined description taken in connection with the drawings forming a part of the specification and in which:

Fig. 1 is a top plan view of one form of the reeling unit;

45 Fig. 2 is a cross-sectional view of a modification of Fig. 1;

Fig. 3 is a perspective view of the rotary winding element of the assembly of Fig. 1;

Fig. 4 is a perspective view of the device in operation; 50 Referring to the drawings, the reel unit 15 of Figs. 1 and 2 comprises the cylindrical annulus 16 vertically disposed relative to the ground and enclosed by the upper frame member 17 and the lower frame member 18. The resulting annular compartment is provided with the front access door 19 and the rear access door 20. These doors are of the sliding type and fit into the grooves 21 and 22 of the door frame elements 23 and 24 formed transversely to the annulus 16 at diametrically opposite sides. Said frames extend outwardly from the annulus 55 16 along generally radial planes. Each of the exit frame sets 23 and 24 are spaced sufficiently whereby the hose can be reeled in and out efficiently. Attached to the lower disc 18 are the roller means 25 and 26 whereby 60 the entire unit can be shifted easily to any desired location.

A spool member 27 is provided to receive the wound hose 28 and comprises the novel winding disc 29, better seen in Figs. 1 and 3, the upper hose retaining disc 30 and the lower hose retaining disc 31 which are secured to the winding disc 29 by the screw means 32. Formed centrally of the retaining discs 30 and 31 are the upper and lower hubs 33 and 34 respectively. The hubs are provided with the bores 35 and 36 which receive the 65 70 axles 37 and 38 which in turn are secured to the upper and lower frame members 17 and 18 respectively. Con-

sequently, the assembly comprising discs 30, 31, 29 and 33 and hubs 34 is rotatable about the axles 37 and 38.

The winding disc 29 is formed of two halves 39 and 40 both having circular outer sides 41 and 42 and S-shaped opposing inner sides 43 and 44 which are spaced sufficiently apart to receive a medial hose portion.

Referring to Fig. 1, it is apparent that with the hose so gripped, rotary motion of the winding member will cause the hose to be wound doubly, each adjacent coil set comprising an inner coil representing the inlet end of the hose and an outer coil representing the front or nozzle end of the hose. Due to the above described winding operation, the hose is reeled from both ends thereby substantially reducing the time and effort required to play out a unit of hose length.

To retrieve the reeled-out hose, there is provided the helical spring 45 which is wound so as to resist the reeling out of hose. One end of the spring 45 being attached to the upper hub 33 whereby clockwise rotation of the winding member 29 puts the spring in tension. So that the hose will be reeled in fully, the spring 45 is set with an initial tension corresponding to the hose in the fully reeled-in position.

To facilitate reeling, roller elements 48 and 49 are provided depending from the upper frame member 17 and located at the front and rear exits respectively. When the hose is fully contained in the closed compartment, the front and rear hose ends are secured by the clips 50 and 51.

In operation, the exit doors 19 and 20 are slid open by the handle means 52 and 53 and the hose ends unfastened. The rear end 54 is attached to the spigot 55 and the nozzle end 56 is taken manually to the desired location. The hose is then reeled out from both ends with the reeling unit 15 adjusting itself to any position. As the hose is played out, the spring 45 is tensioned and when the hose ends 54 and 55 are released, the spring 45 will actuate the winding unit 29 to retrieve the reeled out hose. When fully retrieved, the hose ends are secured by the clips 50 and 51, the doors 19 and 20 are closed and the unit is ready for storage.

Because of the unique structure hereinabove described, elements such as hoses can be reeled easily, rapidly and be contained in a compact portable unit whereby the contents are protected from the weather. While various changes may be made in the detailed construction, it shall be understood that such changes shall be within the spirit and scope of the present invention as defined by the appended claims.

Having thus set forth and disclosed the nature of this invention, what is claimed is:

1. A hose reeling unit comprising an annular compartment having parallel annular sides, aligned axle means secured in opposing relation to the interior portion of said sides, a reeling structure swivelled about said axle means having relative rotary motion thereto, said reeling structure comprising parallel spaced discs each disc having a central hub whereby each disc may be swivelled about the axle means, said discs being interconnected centrally by a winding disc, said winding disc having an interior hose gripping means and a circular exterior, the hose being retained medially by the gripping means, whereby rotary motion of the disc will cause the hose to be wound about the disc exterior in two sections, each of said sections corresponding to one of the hose ends, including exit means for each hose end and roller means attached to the bottom of the compartment whereby the unit can be readily shifted.
2. The combination, as in claim 1, wherein the gripping means is in the form of an S-shaped groove.
3. A hose reeling unit comprising a support provided with a pair of oppositely disposed bearing members, aligned axle means rotatable in said bearing members, a reeling structure swivelled about said axle means having relative rotary motion thereto, said reeling structure comprising parallel spaced discs, each disc having a central hub whereby each disc may be swivelled about the axle means, said discs being interconnected centrally by a winding disc, said winding disc having an interior hose gripping means and a circular exterior, the hose being retained medially by the gripping means, whereby rotary motion of the disc will cause the hose to be wound about the disc exterior in two sections, each of said sections corresponding to one of the hose ends, and roller means attached to the bottom of said support whereby the unit may be readily shifted.
